UNITED STATES PATENT OFFICE.

OLIVIA V. TOLEBERT, OF FRY'S MILL, ARKANSAS.

SKIRT MARKER.

Application filed January 7, 1927. Serial No. 159,632.

This invention relates to devices for marking skirts for uniformly obtaining predetermined lengths thereof.

An object of the invention resides in providing a device for marking skirts, in which a suitable mechanism for receiving the lower edge of a skirt and having a means forming a part thereof for holding suitable marking elements is adapted for use by a person fitting a skirt to herself, to obtain the proper marking for the lower edge of the skirt, so that in the completed form, it will hang an even distance above the floor.

The invention further comprehends the provision of a marking device for skirts in which a suitable and readily adjustable chalk holder is provided mounted on suitable adjustable supporting means adapted to encircle the feet and limbs of a person being fitted with a dress, and a cooperating structure encircling the marking device, adapted to engage the lower edge portion of the dress with the dress interposed between the marking device and the last mentioned structure, so that the said structure may be moved to engage the lower edge of the dress on one side with the marking device on the opposite side, in order that the person wearing the dress can, without assistance, obtain proper markings for the length of the dress all around the lower edge thereof.

The invention comprehends numerous other objects residing in the particular details of construction and relation of the parts which are more particularly pointed out in the following detailed description and claims, directed to the preferred form of the invention, it being understood however, that various changes in the size, shape, and arrangement of the parts may be made without departing from the spirit and scope of the invention as hereinafter set forth.

In the drawings forming part of this application:—

Figure 1 is a plan view of the skirt marker with the parts shown in operative relation.

Fig. 2 is a side elevational view showing a portion of the chalk holder portion of the adjusting and holding mechanism therefor, with one of the supporting standards.

Fig. 3 is a sectional view taken substantially on the line 3—3 of Fig. 1.

Fig. 4 is a detail perspective view of one

group of members in disassembled relation which are used for the construction of the chalk holder.

Fig. 5 is a sectional detail view through the chalk holder, taken on the line 5—5 of Fig. 1, and showing the separator bar for the holder in operative position.

Fig. 6 is a disassembled side elevation of one of the supporting standards for the chalk holder showing the provisions of the markings so that the holder may be set in a predetermined distance above the surface or floor on which it is supported.

Fig. 7 is a plan view of the chalk holder opening device prior to application to the chalk holder shown in dotted lines for moving into the operative position as shown in Fig. 5.

Fig. 8 is a fragmentary elevation of the outer side of the adjustable holder for the skirt adapted for cooperation with the chalk holder in the marking of the skirt.

A chalk holder is indicated at 1, which is annular in form and adjustable in size throughout predetermined limits.

This chalk holder is formed of a pair of duplicate ring sections secured together in relative angular relation by the resilient connectors 2, as clearly shown in Figs. 3 and 5. Each of these rings is formed of a plurality of sections 3 and 4 respectively, which are illustrated in detail in Fig. 4, which are assembled in alternate relation with the ends extending in overlapping relation.

The opposite end portions of each of the strips 3 and 4 which are of arcuate form are provided with elongated slots 5 through which suitable securing bolts 6 are adapted for insertion in order to adjustably connect the strips in assembled ring-forming relation.

The size of the ring is adjusted by loosening the bolt 6 and moving the sections 3 and 4 into greater overlapping relation to the extent permitted by the slots 5 for decreasing the size of the ring or moving them out of overlapped relation for increasing the size of the ring, the bolt 6 being tightly secured to the strip for locking them in a set position.

Each strip is formed in the central portion with an opening 7 for receiving the securing means to attach the rings to the resilient members 2. The strip 4 at opposite sides

of the openings 7 are provided with openings 8 receiving the securing means for attaching the laterally extending feet 9 on the V-shaped supporting bracket 10 thereto. 5 These brackets are adapted to extend inwardly in radial relation and inclined relative to the plane of the ring and in the central portion are formed with suitable openings receiving the securing bolt 11, for 10 mounting the chalk holder in assembled relation with the supporting structure as will now be desired.

The supporting structure for this chalk holder as illustrated in the drawings, includes three supporting standards indicated generally by the numeral 12. These standards include base plates 13 with which are formed upright arcuate plate members 14 as clearly illustrated in Figs. 2 and 6. These 20 arcuate plate members are formed for a substantial portion of their length with slots 15 and 16 in the central and side portions thereof, the slot 15 being in the central portion and the slots 16 being in the side portion 25 thereof, and opening through the upper end. Supplemental plate members 17 are provided with longitudinally extending slotted portions 15' and 16' which are adapted to register with the slots 15 and 16 30 in the plate member 14.

Suitable securing elements 18 extend through the slots 16 and 16' in registering relation and serve to adjustably secure the arcuate plate member and supplemental 35 plate member in a desired position of adjustment, so that the supporting standards may be varied in height within predetermined limits. Each of these supporting standards is provided with suitable scale 40 markings to indicate the height of adjustment for the chalk holder above the surface on which it is supported, for a purpose which will presently be described.

To hold the standards in proper relation 45 with one another for supporting the chalk holder, an adjustable split ring member 20 is provided with a plurality of longitudinally extending slots 21 which receive the bolts 11 also adapted to extend through the slots 50 15 and 15' in the standards following which they are secured in the central portion of the V-shaped bracket 10 in order that in the secured relation of the parts, the ring 20 and the bracket 10 will be firmly secured to the 55 standard in a desired position of adjustment.

The ring 20 is adjusted at one side, in condensation with the adjustment of the side of the chalk holder, through the overlapping end portions thereof, being secured in adjusted relation by the set screw 22, extending 60 through an elongated slot in one end portion of the ring. By means of the sliding adjustment provided for the bolt 6 in the slots 21, a uniform adjustment is possible 65 throughout the circumference of the ring so

as to preserve its circular shape and thus retain its uniformly spaced relation with respect to the chalk holder.

The supporting standard 12 for the chalk holder is formed of a sufficient height so 70 that the chalk holder may be placed from one to twenty-four inches above the supporting surface or more if desired. The holding ring 20 is of a size sufficient to enable it to readily fit around the feet and limbs 75 of the wearer, being fitted with a skirt, in such a manner that it may be closely fitted to the limbs in order to normally lie out of range of contact with the lower end of the dress on the wearer.

This adjustment of the parts may also be made so that the standards will not interfere with the hanging of the dress being fitted. With the parts adjusted in this manner to the wearer of the skirt being fitted, 80 in order to obtain the proper marking for the length of the skirt, the chalk holder may be adjusted with respect to the ring 20 after loosening the bolts 6, the set screws 22 and the bolts 11, so that each section of the chalk 85 holder may be adjusted simultaneously whereby the same will lie within and under the skirt for marking the inside thereof in the manner in which it naturally hangs on the wearer.

When the chalk holder is adjusted to proper size, the bolts 6, 11, and the set screw 22 are all tightened to retain the parts in rigid adjusted relation.

A skirt holder indicated generally at 23 100 includes a pair of sections 24 and 25 respectively of substantially semi-annular form hingedly connected together at 26 so that they may be easily moved into and out of annular relation outside of the chalk holder 1. Each of the sections 24 and 25 are formed of a plurality of relatively wide plate members 27 secured in overlapped relation by suitable securing screws 28 extending through the slotted portions 29 formed at the end of the sections 28 and at opposite sides thereof, as clearly shown in Fig. 8 of the drawings.

These plate members 27 are of arcuate form in cross section as illustrated in Fig. 3 as well as lengthwise in order to conform to the annular form in properly adjusted relation of the chalk holder 1. The plates, members 27 of each of the sections 24 and 25, are provided at a pair of spaced points with suitable U-shaped bracket members 30, having the end portions suitably secured thereto, while the central portions are formed with threaded openings receiving the set screws 31 extending through the slotted portion 32 of the uprights 33 adapted to support said skirt holder in a desired position of adjustment on the floor or other supporting surface.

These uprights for the skirt holder are formed of a pair of adjustable sections 34 130

and 35 which may be of any suitable height found most desirable for the purpose, the sections 34 of which are provided with supporting feet 36 resting on the floor or supporting surface for the device.

As the ring members of the chalk holder are normally moved by the resilient bracket members into contact relation at the inner edges with the body portions extending in angular relation as illustrated in the drawing, it is necessary to spring the same apart against the tension of the brackets in order to insert the chalk for marking a skirt. Angularly faced sections of chalk such as indicated at 37 in Fig. 3, are used in connection with the chalk holder, and in use are clamped by the action of the bracket members 2 between the rings of the holder 1.

In order to insert the chalk sections throughout the groove formed between the rings of the holder, for marking a skirt, this invention provides a spreader for the rings shown in Fig. 7 at 38. This spreader includes a pair of substantially semi-annular strips 39 having the ends connected by a suitable set screw 40 extending through the slotted end portions 41 to permit adjustment of the size of the spreader while the opposite end portions are secured in adjustable spaced relation by the stop member 42 and the set screws 43 extending through the slotted portion of the stop member and the slotted ends of the strip 39.

These strips 39 at predetermined points carry wedge members 44. The chalk holder is shown in dotted lines in Fig. 7, with the spreader in position for engagement between the two rings forming said holder for spreading the rings apart in order that the chalk sections may be inserted therebetween and placed in clamped relation. From the position of the parts shown in Fig. 7, the spreader is contracted after the chalk sections are positioned with the tapered ends between the rings so that the strips 39 will force the wedges between the rings and spread the same apart simultaneously with pushing the chalk sections between the two rings.

After the chalk sections are positioned between the separated ring sections, the spreader is then removed to permit the same to move together under the resilient action of the bracket members 2 which will engage and clamp the chalk therebetween as shown at 37 in Fig. 3, as a result of which the chalk holder is ready for the marking operation.

When the person desiring to fit a skirt upon herself has adjusted the chalk holder to the proper height on the standard and adjusted the holding ring 20 and the chalk holder to the proper size as heretofore set forth, the chalk is then placed in the chalk holder for the marking operation. The adjustable skirt holder is also adjusted with the

sections 24 and 25 secured in proper adjusted relation and at the proper height to be positioned in the same horizontal plane as the chalk holder in the manner as illustrated in Fig. 3, and the sections moved outwardly 70 relative to one another on the hinge connection 26, the party fitting the skirt then steps into the ring 20 and allows the skirt when it is fixed in proper relation, to hang outside of the chalk holder 1. When the body is standing erect with the skirt in the proper adjusted relation on it, the arms are used for grasping with the hands and moving the sections 24 and 25 of the skirt holder into the position shown in Figs. 1 and 3, 80 which engages the outer face of the dress over the chalk holder and it being moved in against the chalk holder forces the dress into contact with the chalk so that it is marked on the inside to the desired length. 85

Following this operation, the sections 24 and 25 are moved apart on the hinge 26 and the dress may then be removed, the marking produced by the chalk indicating the position for forming the hem so that it 90 will be even and the same distance above the ground or floor surface all around the lower edge.

Coats, gowns, or other garments may also be marked for obtaining proper length there- 95 of with the use of this device.

Where two persons use the device, one of them being a fitter, the spreader ring is usually positioned in engagement between the rings of the chalk holder 1 and the set 100 screws 40 and 43 adjusted to lock the sections in this position, and then the fitter can position the lower edge of the dress over the spreader ring and mark the same by hand with the piece of chalk over the ring. 105

This operation requires a fitter for the person being fitted, to obtain the proper marking of the skirt or other garment, while with the first method of use, the person being fitted can obtain the proper markings for length herself, without the necessity of the fitter.

It should thus be readily obvious that a highly novel construction has been provided for obtaining and marking the proper length 115 of garments, and particularly skirts and the like with a structure in which all of the parts are adjustable within desired limits, and by which a dress maker or the like may readily fit skirts or other garments on herself without the use of a fitter or other person to do the marking.

Having thus described my invention, what I claim as new is:—

1. A device of the class described comprising a pair of rings forming a chalk holder, each ring consisting of a pair of annular sections, resilient means secured to said rings and normally retaining the same in contact, each of said rings being adapted 130

to have the sections adjusted relative to one another for varying the size of the holder, means for adjustably supporting said chalk holder above a suitable supporting surface, 5 and means adapted for cooperation with said chalk holder to engage a garment for marking purposes.

2. A device of the class described, comprising a chalk holder adapted for adjustment in size, said chalk holder being of annular form, means for adjustably supporting said chalk holder above a supporting surface, a garment holder for cooperation with said chalk holder to mark a garment carried by 10 said chalk holder, said garment holder being formed with a plurality of adjustable sections adapted to vary the size thereof, and means for independently and adjustably supporting said garment holder on the supporting 15 surface for the chalk holder.

3. A skirt marker, comprising a chalk holder, having a pair of duplicate rings, each of said rings being formed of a plurality of arcuate sections, means adjustably connecting adjacent sections in circular ring forming relation, the adjustment of each section relative to the other varying the size of the chalk holder, resilient connectors for said 20

rings normally retaining said rings engaged with chalk positioned therebetween, a holding ring adjustable in size, (means connecting the chalk holder to the holding ring, a plurality of supporting standards adjustably supporting said holding ring, and means for engaging a skirt with chalk positioned in 25 said chalk holder.

4. A skirt marker comprising an annular chalk holder having a pair of duplicate rings, each of said rings being formed of a plurality of sections, means adjustably connecting adjacent sections in circular ring forming relation, the adjustment of each section relative to the other varying the size of the chalk holder, resilient connections for said rings normally retaining the rings engaged with chalk positioned therebetween, a holding ring adjustable in size and smaller than 30 said chalk holder arranged concentrically within said chalk holder, means connecting the chalk-holder to said holding ring, and a plurality of vertical supporting standards adjustably mounting said holding rings, and means for engaging a skirt with chalk positioned in the holder.

In testimony whereof I affix my signature.
OLIVIA V. TOLBERT.
